UNITED STATES PATENT OFFICE.

HARRY WALLACE THOMAS, OF INDIANA, PENNSYLVANIA.

DESIGN FOR A DISH OR ANALOGOUS ARTICLE.

Application filed March 12, 1927. Serial No. 21,121. Term of patent 7 years.

To all whom it may concern:

Be it known that I, HARRY WALLACE THOMAS, a citizen of the United States of America, and a resident of Indiana, in the county of Indiana and State of Pennsylvania, have invented a new, original, and ornamental Design for a Dish or Analogous Article, of which the following is a specification, reference being had to the accompanying drawings, forming a part thereof, and in which—

I claim:

The ornamental design for a dish or analogous article, as shown.

HARRY WALLACE THOMAS.
